Attorney.

UNITED STATES PATENT OFFICE.

LAURENCE GATES, OF ELYRIA, OHIO.

BURIAL-VAULT.

1,376,615.

Specification of Letters Patent.

Patented May 3, 1921.

Application filed March 3, 1920. Serial No. 362,904.

To all whom it may concern:

Be it known that I, LAURENCE GATES, a citizen of the United States, residing at Elyria, in the county of Lorain and State of Ohio, have invented certain new and useful Improvements in Burial - Vaults, of which the following is a specification.

This invention relates to burial vaults formed of cement material and adapted to 10 inclose burial caskets and to be tightly sealed; and it consists in the novel construction and combination of the parts herein-after fully described and claimed.

In the drawings, Figure 1 is a front view 15 of a burial vault constructed according to this invention. Fig. 2 is a plan view of the same. Fig. 3 is a cross-section through the vault, taken on the line 3—3 in Fig. 2.

The body portion 2 of the vault is 20 rectangular in form, and it has ribs or projections 3 on its bottom for the casket to rest on when lowered into it. The body portion is open at top, and it has a seal 4 formed around its top edge. The seal is a groove 25 which is arranged vertically over the side walls 5, and it is formed between an outer side portion 6 and an inner side portion or lip 7 of less height than the part 6. The bottom of the seal is rounded, and its groove 30 is slightly tapered.

The cover 8 is preferably arch-shaped in cross-section, and it has a vertical flange 9 which projects around it. This flange is slightly tapered, and it has a rounded bottom which fits in the rounded bottom of the groove or seal. The body portion and cover are formed of any suitable cement or concrete material, and wires 10 or other suitable reinforcing devices are inserted in 40 their thicknesses. The cover has handles 12 formed on or secured into it, for raising and lowering it, and the body portion has pro-

jecting lugs 14 formed integrally with it and arranged at its angles, for the purpose of lowering it into a grave. 45

When the cover has been lowered into place, the sealing groove is run full of liquid cement 15 of any approved composition. When the cement 15 sets it seals the vault tightly and prevents the cover from being 50 removed.

The body portion and cover are made as thin and light as possible without making them of insufficient strength, and the arrangement of the seal vertically over the 55 sides of the body portion permits the weight of the cover to be borne by the sides, so that the side portions are relieved of strain and are not liable to be split off or broken.

What I claim is:

A burial vault, comprising a body portion having a sealing groove at its top, said groove having a rounded bottom arranged in a vertical plane directly over the vault side, the inner side wall of the said seal being of less height than its outer side wall and being inclined inwardly and the side walls of the said seal being arranged to project laterally one on each side of the vault side which is relatively thin, and a cover 70 provided with a tapering flange having a rounded bottom which rests continuously in contact with the rounded bottom of the groove and supports the cover and prevents sealing material from flowing into the vault, 75 the sides of the flange being supported out of contact with the sides of the sealing groove, and the space between the flange and the outer side of the seal being adapted to receive sealing material. 80

In testimony whereof I have affixed my signature.

LAURENCE GATES.
